UNITED STATES PATENT OFFICE.

JASON EVANS LIPPINCOTT, OF ALEXANDRIA, INDIANA.

DESIGN FOR A LAMP-CHIMNEY.

SPECIFICATION forming part of Design No. 21,983, dated November 8, 1892.

Application filed May 20, 1892. Serial No. 433,774. Term of patent 14 years.

To all whom it may concern:

Be it known that I, JASON EVANS LIPPINCOTT, a citizen of the United States, residing at Alexandria, Madison county, Indiana, have 5 invented a new and original Design for Lamp-Chimneys, of which the following is a specification.

My invention relates to a design for lamp-chimneys made of glass, and is particularly 10 applicable to those of substantially-circular cross-section.

In the drawings herewith, exhibiting a lamp-chimney to which my design is applied, I show in Figure 1 a perspective elevation of a chimney of the foregoing type, terminating above 15 in a flaring or trumpet-shaped top with a "crimped" edge ornamentation, my design being exhibited as applied thereto; Fig. 2, a detail plan view of the same.

20 The design consists in a horizontal marginal contrasting band or stripe upon the surface of the glass chimney in connection with a beaded, crimped, or otherwise ornamented

edge covered by the band. The band is placed upon or wrought into the surface of the chimney, following the contour of the raised ornamentation of the upper margin and extending downward therefrom to a sharply-defined horizontal line or edge contrasting in color with the remaining surface. 25

I claim as my invention and desire to secure by Letters Patent of the United States—

The herein-described design for a glass chimney, consisting of a horizontal contrasting band or stripe upon the surface at and extending 30 below the upper edge of the chimney in connection with a beaded or crimped edge ornament covered by said band or stripe, substantially as set forth.

In testimony whereof I have hereunto set 35 my hand in the presence of two subscribing witnesses.

J. EVANS LIPPINCOTT.
